Patented Feb. 8, 1916.

UNITED STATES PATENT OFFICE.

DAVID PETRI-PALMEDO, OF BRIDGEPORT, CONNECTICUT, ASSIGNOR TO ELECTRIC COMPOSITOR COMPANY, OF NEW YORK, N. Y., A CORPORATION OF NEW JERSEY.

TYPOGRAPHIC MACHINE.

1,171,136.

Specification of Letters Patent.

Patented Feb. 8, 1916.

Application filed May 15, 1915. Serial No. 28,258.

To all whom it may concern:

Be it known that I, DAVID PETRI-PALMEDO, a citizen of the United States, residing at Bridgeport, in the county of Fairfield and 5 State of Connecticut, have invented a certain new and useful Improvement in Typographic Machines, of which the following is a full, clear, and exact description.

This invention relates to typographic machines of the sort which contain magazines in which matrices are stored, and from which they are released, one by one, by the manipulation of finger keys. Such machines also contain mechanisms that act automatically to assemble the released matrices in line; to justify said line; to cast a type bar from said justified line; to disintegrate the line; and to distribute the matrices to their respective magazines; and it also contains 10 means by which the matrices are transferred from one to the other of said mechanisms. In machines of this character, the matrices as they are released from their magazines fall upon a traveling gatherer belt by which 15 they are carried to and discharged into what is known as an assembler throat. They fall through this throat to the action of composing mechanism that usually includes a rotating star wheel packer by which 20 the matrices are moved along onto the assembling rails and past retaining pawls which prevent any return movement. Matrices must vary in thickness in accordance 25 with the width of the character depressions in their edges. To facilitate the distribution of the matrices, each matrix is formed with a combination web,—and these webs must be of the same thickness on all matrices. Each web is produced by a recess in 30 one side of the matrix—and obviously these recesses must be of different depths on matrices of different thickness. Heretofore all matrices have been formed with the web producing recesses in the sides which are 35 the following sides during the composition of the matrix lines. This renders the matrices better suited for coöperation with the line disintegrating mechanism, and with the distributing mechanisms, such as are 40 commonly used. In machines of this character, it is necessary for the assembling of matrices as heretofore made, that the assembler throat be made of variable width 45 in order that it may function properly with 50

matrices of different widths in the same or 55 different fonts.

The present invention relates particularly to the composing mechanism, including the assembler throat of such mechanism; and it includes particularly an assembler 60 throat which may remain constant in width, but will nevertheless perform its functions in connection with matrices of different widths in the same or different fonts—this being possible because the matrices adapted 65 for use with said composing mechanism have their web forming recesses, (which vary in depth), in the leading sides of the matrices during composition, and extended from top to bottom of the matrices—and 70 because for the first time said recesses and webs are utilized to perform useful functions during composition.

In the drawing, Figure 1 is a side elevation of the assembler throat and other associated matrix assembling or composing mechanism of a typographic machine of the character specified; Fig. 2 is a sectional plan of said mechanism in the plane of line 2—2 on Fig. 1; Fig. 3 is a perspective view 75 which shows the front edge and the "following" side of a matrix adapted for use with said assembling mechanism; and Fig. 4 is a perspective view, which shows the 80 rear edge and leading side of a similar but 85 thinner matrix.

The matrices shown in Figs. 3 and 4 adapted for use with the assembling mechanism shown in Figs. 1 and 2, vary in thickness as stated. Each has an inverted character depression 16 on its rear edge. A vertical channel 17 is formed in that side of each matrix which is in the lead as the matrices are passing through the composing mechanism. The channel 17 extends from 90 top to bottom of each matrix; and the channels are of different depth on matrices of different thickness, so that the webs 18 which are formed as the result of said channels, shall be of the same thickness on all 95 matrices, regardless of the thickness of the said matrices. The web of each matrix is flush with that side of said matrix which is the following side during composition, and said following side is a plain surface substantially as shown. Two ears, 10 and 12, project respectively forward and rearward near the upper ends of the matrix, and two 100 105

other ears, 14 and 15, project respectively forward and backward near the lower edge of each matrix, and preferably the following faces of these ears are flush with the plain following side of the matrix of which they are parts.

The assembler throat consists of a lower member A and an upper member B; and the opposed surfaces of these members are so shaped that each matrix after it is discharged into said throat from the gatherer belt will be turned therein into a substantially erect position and delivered in this position from the lower end of said throat.

The lower member is preferably as wide or wider than each matrix, although the width of this member is of no great consequence. The width of the upper member B, however, must be slightly less than the width of the vertical channel 17 in each matrix. Therefore, as each matrix is discharged from the gatherer belt C into said assembler throat, the matrix will straddle said upper throat member; or, in other words, the throat member will project into said channel as the matrix is passing through the throat. There must be room enough between these two throat members to permit the web of each matrix to pass. Inasmuch as the webs are all of the same thickness, it is evident that the width of the throat, that is to say, the distance between the two members thereof, may remain constant; and the throat will perform its function regardless of any variation in the thickness of the matrices themselves. The matrix will be guided by said upper throat member, and therefore the throat does not require side members to perform its function. Below this throat and in position such that matrices as delivered from the throat will drop upon it, is the constantly rotating star wheel packer G. This packer lies between two inclined assembly rail extensions E E, and slightly to the right of the assembling rails F F themselves. When a matrix falls from the assembling throat, its ears will always engage at the same points on these rail extensions. The matrices will always be engaged at the same points by the arms of the star wheel packer G. The matrices will be pushed to the left by the arms of the star wheel packer, their lower ears sliding on these extension rails, and dropping from said extension rails onto the assembling rails.

The rear or following sides of the matrices being ungrooved or unrecessed, will always be moved to the same position by the star wheel packer G, and to such position that the upper ears of the matrices will be caused to engage the beveled inner faces h of the spring pawls H, and push them aside, and pass them; whereupon said spring pawls will fly back behind these matrices,

and prevent any backward motion of the matrices. The inclined surfaces of the rail extensions E E end above the rails F; and then extend vertically downward to said rails. This forms the vertical shoulders e, which are so located that when the lower matrices drop off of the inclined surfaces of the rail extensions onto the assembling rails, these shoulders will be behind the lower ears and will prevent any backward movement of them.

Having described my invention, I claim:

1. In a typographic machine, the combination of matrices which are of different thicknesses but have between their front and rear edges webs of the same thickness on all matrices produced by vertical channels of different depths on matrices of different thickness, each of said matrices having its said channel extended from top to bottom, and formed in said side of the matrix which is the leading side as the matrix is going through the composing mechanism, with an assembler throat having relatively fixed upper and lower members of which the width of the upper member is slightly less in width than the vertical channels in said matrices.

2. In a typographic machine, the combination of matrices which are of different thicknesses but have between their front and rear edges webs of the same thickness on all matrices produced by vertical channels of different depths in matrices of different thickness,—each of said matrices having its said channel extended from top to bottom, and formed in said side of the matrix which is the leading side as the matrix is going through the composing mechanism, with an assembler throat having relatively fixed upper and lower members of which the width of the upper member is slightly less in width than the vertical channels in said matrices, and means for delivering the matrices into said throat with their grooved sides uppermost.

3. In a typographic machine, the combination of matrices which are of different thicknesses but have between their front and rear edges webs of the same thickness on all matrices produced by vertical channels of different depths in matrices of different thickness,—each of said matrices having its said channel extended from top to bottom, and formed in that side of the matrix which is the leading side as the matrix is going through the composing mechanism, with an assembling throat having relatively fixed upper and lower members of which the width of the upper member is slightly less in width than the vertical channels in said matrices, a rotating star wheel packer located beneath said throat, and assembling rails adjacent to said packer onto which the packer will push the matrices discharged from said throat.

4. In a typographic machine, the combination of matrices which are of different

- thicknesses but have between their front and rear edges webs of the same thickness on all matrices produced by vertical channels of different depths in matrices of different thickness,—each of said matrices having its said channel extended from top to bottom, and formed in said side of the matrix which is the leading side as the matrix is going through the composing mechanism, with an 5
10 assembling throat having relatively fixed upper and lower members of which the width of the upper member is slightly less in width than the vertical channels in said matrices, a rotatable star wheel packer located beneath said throat, two inclined extension rails lying respectively in front of and behind said star wheel packer, and assembling rails alined with said extension rails.
15 5. In a typographic machine, the combination of matrices which are of different thicknesses but have between their front and rear edges webs of the same thickness on all matrices, produced by vertical channels of 20
25 different depths on matrices of different thickness, each of said matrices having its

said channel extended from top to bottom, and formed in said side of the matrix which is the leading side as the matrix is going through the composing mechanism, with an 30
35 assembling throat having relatively fixed upper and lower members of which the width of the upper member is slightly less in width than the vertical channels in said matrices, a rotatable star wheel packer located beneath said throat, two inclined extension rails lying respectively in front of and behind said star wheel packer, and assembling rails alined with said extension rails, the delivery ends of said extension 40
45 rails being in a plane slightly higher than the receiving ends of said assembling rails, and two spring-actuated retaining pawls above the delivery ends of said extension rails and past which the packer will push said matrices.

In testimony whereof, I hereunto affix my signature in the presence of two witnesses.

DAVID PETRI-PALMEDO.
